UNITED STATES PATENT OFFICE.

GEORGE H. BENNETT, OF CINCINNATI, OHIO.

PUMP.

SPECIFICATION forming part of Letters Patent No. 330,669, dated November 17, 1885.

Application filed August 15, 1885. Serial No. 174,465. (No model.)

To all whom it may concern:

Be it known that I, GEORGE H. BENNETT, a citizen of the United States, residing at Cincinnati, in the county of Hamilton and State 5 of Ohio, have invented certain new and useful Improvements in Pumps, of which the following is a full, clear, and exact description, reference being had to the accompanying drawings, forming part of this specification.

10 My invention relates to an improvement in that class of pumps in which air is forced into a vessel containing the water and the water driven out and lifted by the pressure of the air.

15 It consists, first, in the novel arrangement and construction of the air-pump for forcing the air into the vessel containing the water; second, in the construction of the reservoir or air-chamber for confining the air and water 20 in the well or cistern; third, in the arrangement and construction of the valves, floats, and balance to permit the escape of air and entrance of water in the chambers automatically; and, fourth, in the novel construction of 25 the pumping-lever or pump-handle.

In the accompanying drawings, Figure 1 is a side elevation, in section, of the frame, air-pump and air-chamber. Fig. 2 is a side elevation of the air-pump above ground, and a 30 front elevation, in section, of the air-chambers in the well, and the floats and automatic cut-off valves for opening and closing the air-chambers. Fig. 3 is a front elevation of the automatic balance for operating the valves. 35 Fig. 4 is a larger sectional view of the cut-off valve and connections.

The same letters of reference are used to indicate identical parts in all the figures.

A is a frame supporting the air-pump. B is 40 an air-cylinder in which works the piston-head C. The lower end of the piston-rod C' is pivoted to the curved reciprocating arm D, which is moved up and down by the lever E. The reciprocating arm D is provided with a 45 cross-piece, d, Fig. 2, the ends of which fit into the upright guides F, by which the piston-rod is held parallel with the cylinder B. The piston-head C is provided with a valve which freely opens upward, so that as the piston 50 is drawn down air enters the cylinder

through the valve, which closes as soon as the piston is moved up by the downward pressure of the air within the cylinder. Connected with the cylinder B by the pipe H is a smaller air-cylinder, G, provided with a piston operated by a reciprocating arm, D', in the same manner as the cylinder B, the arm D' being connected to the lever E, as shown. The fulcrum end of the lever or pump-handle E is in the form of a sector pivoted at its center to 60 the frame at e. To one arm of this sector is attached the reciprocating arm D, and to the other the arm D', so that as the arm D is moved up by the lever E the reciprocating arm D' is moved down, and vice versa. The piston-head of the cylinder G is made solid and tight. At the head of the cylinder B, between the cylinder and pipe H, is a loose valve, b, opening upward, so as to give free egress to the air, but to prevent its ingress from the pipe H. 65 As the piston C is driven up in the cylinder B, air is forced through the valve at b and the pipe H into the cylinder G. The cylinder G is made about one-half the size of the cylinder C, so that the air being forced into the 70 cylinder G is compressed to one-half its atmospheric volume. The relative size of the two cylinders may be varied, though I find that about two to one produces the most satisfactory result. 75

Connected with the pipe H is a pipe, I, provided with a valve at h. This valve at h is weighted or gaged to remain closed and resist the pressure ordinarily produced by the air from the cylinder B alone, but to open when 80 pressure from the cylinder G is added to the pressure from the cylinder C, and permit the air to pass through the pipe I. It will often be found that the backward pressure from the pipe I will alone hold the valve at h closed 85 against the pressure from the cylinder B until the cylinder G has been filled with compressed air.

The pipe I leads to and opens into the top of an air chamber or vessel, K. This air-chamber K is sunken in the well or cistern below the surface of the water, usually near the bottom. At its bottom it has a valve, L, opening freely upward, through which it fills with water. M is an open tube or pipe, the lower 90

end extending almost to the bottom of the chamber K, the upper end being carried to any point to which it is desired to pump and discharge the water. As the lever E is worked and the air driven through the tube or pipe I into the chamber K, it presses downward on the water and forces it out through the pipe M. By the use of the two cylinders C and G the force of the pump is greatly increased, the power produced being almost double in proportion to the power consumed in operating the lever, the natural elasticity of the air making the force even and constant.

While air is being forced into and water out of the chamber K the valve L remains closed by the downward pressure on it, and when the water has all been forced out of the chamber the air must be allowed to escape to permit it to refill with water. This may be done by opening the cock N in pipe I, when the air will escape rapidly, or a small opening in the chamber may be made, as shown at k. This opening is made so small as not to permit the escape of sufficient air to materially affect the working of the pump when in operation, but to allow the air to escape slowly when the pump is idle. The air thus escaping into the water of the well passes up and out and serves to aerate and purify the water. Where desired, a cock may be placed in the top of the chamber K and controlled by a rod extending up out of the well, and this cock may be opened to permit the rapid escape of the air into the water in the well for the purpose of aerating it.

The air-pump may be located at any point and at any distance from the well. The pipe I may be made flexible and the air-pump moved about as convenient; or the same pump may be used for several wells or cisterns by connecting them all with the pipe I. If the air-pump is large enough, water may be pumped from all at the same time; or by simple stop-cocks in the pipe I the connection with one or more of the wells may be shut off at pleasure. By the use of the sunken chamber K the pump may be used to lift water from any creek or lake, the pump remaining at any distance away. A pump operated by steam and located upon land may be connected by pipes with a chamber, K, out in a lake a mile or two from land, and pump as effectively as if situated immediately over the chamber K.

Where it is desired to avoid the loss of time caused by waiting for the chamber K to refill with water after having been emptied—that is, to make the flow of water constant—I use two chambers, P and Q, Fig. 2. The air-pipe I then, instead of opening directly into the chambers P and Q, opens into a valve-chamber, R, attached to any convenient support above the chambers by the lugs r r r. From this valve-chamber extend two pipes, T and V, one into the chamber P and the other into the chamber Q. Within this valve-chamber R is a valve or key, R', which may be turned to connect the pipe I with the pipe T or pipe

V, as desired. The escape-pipe M is also divided so as to connect with both the air-chambers P and Q by the pipes m m. When the valve R' is turned to connect the pipe I with the pipe T and chamber P, as shown in Fig. 2, the air is forced by the pump into the chamber P and the water out through the pipes m m. When the chamber P is emptied, the valve R' is turned to connect the chamber Q in like manner. To permit the rapid escape of air from either chamber when not in use, the valve R' is cut away, as shown, so that when the valve is turned to connect pipe I with pipe T and chamber P the air from chamber Q may escape through pipe V and out through U. In Fig. 2 the openings S and U are shown extended out in different directions, so as to distribute the escaping air through the water in the well for the purpose of aerating and purifying it. By simply turning the valve R' the air-pump is connected with either chamber, while an escape is provided for the air from the other chamber to permit it to rapidly refill with water. By this arrangement there is always a chamber full of water to be drawn from, and it is not necessary to wait for a chamber to refill. Where it is desired, of course another chamber may be added and connected with the pump in the same way. In order to make this valve R' act automatically to connect either chamber, as the condition of the water requires, I provide a T-shaped yoke, X, pivoted to an upright support at x. From the ends of the arms of this yoke are suspended chains or cords y y. In each of the chambers P and Q is a suitably-weighted float, Z Z', which rests on the water in the chamber, and of course rises or falls therewith. From these floats are arms passing through the top of the chambers and attached to the chains y y. Pivoted to the support at the same point as the yoke X is a balancing-arm, O, weighted at its upper end, and whose lateral swing is limited by the guide O'. The lower end of this swinging balance extends below the valve R', and is provided with lateral arms o o, at the ends of which are projecting pins or lugs. Attached to the valve R' is a lever, R'', extending downward, and by which the valve is turned in the chamber R. As the swinging balance O is turned to the right or left, the pins or lugs on the arms o o catch the lever R'' and swing it to the right or left, and thus turn the valve R'.

In operation, as the chamber P, Fig. 2, from which water is being pumped while chamber Q is refilling, is emptied, the float Z sinks lower and lower. As the float Z is supported and lifted by the water entering the chamber Q, the sinking float Z will draw the arm X' lower and lower with it. The guide O' and the chains y y are so adjusted in length that just before the float Z reaches the bottom of the chamber P the weight at the upper end of the swinging balance O will pass the center of gravity and swing or fall to the opposite limit of the guide O'. When it thus swings, the lug

or pin on the arm *o* strikes against the lever *R''*, so as to close the connection between the pipe *I* and the pipe *T* and open the connection between pipe *I* and pipe *V*, leaving the pipes *T* and *S* open for the escape of the air into the chamber *P*. The air being thus permitted to escape freely, the chamber *P* will fill with water as rapidly or more rapidly than the chamber *Q* can be emptied. As the chamber *Q* is emptied, the float *Z* will again sink, and the action of the swinging balance will be reversed. By this means there is always a supply of water in one of the air-chambers, and the full chamber is automatically connected with the air-pump and a constant supply and uninterrupted flow of water secured.

The escaping air may be distributed by the pipes *S* and *U* through the well or cistern so as to constantly aerate the water and keep it pure and sweet.

By using air for forcing the water in the manner described the moment the pump stops all water in any of the pipes sinks to the level of the water in the well, and there is no water left above ground to freeze. There are no valves exposed to the action of the water under pressure, to be worn and cut by the sand in the water. The valve *L* at the bottom

of the chamber, by reason of its simplicity and work, is subject to only a minimum wear, and will last without repair for an indefinite time.

Having thus fully described my invention, I claim—

1. The chambers *P* *Q*, situated beneath the surface of the water and connected with an air-pump, in combination with the yoke *X*, carrying the weighted balance *O* and having its arms *X' X''* attached to floats in the chambers, and at its lower end a cross-bar provided with lugs at each end to operate the valve *R'*, substantially in the manner and for the purpose described.

2. The arm *O* and yoke *X*, swinging on the same pivot, the arms of the yoke *X* being attached to floats *Z Z'*, and having at one end a weight and at the other a cross-arm provided with lugs to catch and turn the valve-arm *R''*, which is attached to and operates the two-way valve *R'* to open and close the connection between the chambers *P* *Q* and air-pump, substantially as described.

GEORGE H. BENNETT.

Correction in Letters Patent No. 330,669.

It is hereby certified that Letters Patent No. 330,669, granted November 17, 1885, upon the application of George H. Bennett, of Cincinnati, Ohio, for an improvement in "Pumps," was erroneously issued to said Bennett; that said Letters Patent should have been issued to the *Bennett & Wilson Manufacturing Company*, as assignee of said Bennett; and that the said Letters Patent should be read with this correction therein that the same may conform to the record of the case in the Patent Office.

Signed, countersigned, and sealed this 5th day of January, A. D. 1886.
